(No Model.)

L. L. SCHUBERT & F. MAIERHOEFER.
HOD.

No. 407,968.

Patented July 30, 1889.

UNITED STATES PATENT OFFICE.

LOUIS L. SCHUBERT AND FREDERICK MAIERHOFER, OF CHICAGO, ILLINOIS.

HOD.

SPECIFICATION forming part of Letters Patent No. 407,968, dated July 30, 1889.

Application filed April 23, 1889. Serial No. 308,246. (No model.)

To all whom it may concern:

Be it known that we, LOUIS L. SCHUBERT and FREDERICK MAIERHOFER, citizens of the United States, residing at Chicago, in the county of Cook and State of Illinois, have invented new and useful Improvements in Hods, of which the following is a specification.

Our invention relates to improvements in sheet-metal hods of the class employed by builders in carrying brick and mortar; and our object is to provide such a hod of an improved construction which shall render it lighter and more durable than the hods of this class hitherto commonly in use.

To this end our invention consists in the construction hereinafter described and claimed.

In the drawings, Figure 1 is a view in side elevation of our improved hod with part of the handle broken away; Fig. 2, a front view of the same, also with part of the handle broken away; and Figs. 3 and 4, sections taken on the lines 3 3 and 4 4, respectively, of Fig. 1, and viewed in each instance as indicated by the arrows.

A is the trough-shaped body portion of the hod, formed of sheet metal and comprising sides A' A', to which is riveted the back A². The sides A' A' are formed together of an integral sheet of metal bent to afford the usual V shape and rounded at the upper forward corners, as shown. The sides A' are strengthened by a continuous rod t of stiff springy metal shaped to conform to the upper and forward edges of the sides and held in place by the turning over of the said edges, as shown. The lower forward part of the body portion is provided on its under side with a re-enforcing plate s, having a lip s', affording a hook whereby to suspend the hod, when desired, upon an elevator.

B B are braces formed of plate metal of preferably springy quality, and shaped to produce, when adjusted as shown, shank portions q, forming between them a socket wherein to secure the handle C underneath the hod-body, and oppositely-projecting arms

q' q², extending flatwise against the sides A', to which they are secured by rivets. The 50 arms q' are curved, as illustrated, and extend to abut against the rod t at the forward end of the body portion about midway between the upper and lower edges of the sides A', where their ends are maintained in rigid 55 relation with the said rod by the flanged edge of the said body portion. The handle C is secured in the socket by bolts x passing transversely through it, as shown.

The body portion A, constructed as described, possesses a degree of elasticity which will prevent it from being broken or losing its shape in the ordinary rough usage to which hods of this class are liable, while the braces B, in addition, owing to their peculiar 65 shape and the manner of their adjustment, strengthen the hod at the points most liable to give out in the use of the device, with the employment of comparatively little metal to add to the weight of the hod and the cost of 70 its manufacture.

D is a broad flat spring, comprising a straight arm p to enter a sheath o, afforded by a strip of flat metal secured at its edges on the under side of the hod, and a free arm 75 p', curved to fit comfortably over the shoulder of the hod-carrier and extending toward the handle. The arm p fits loosely in its sheath, whereby the spring may be readily attached and removed or adjusted toward and 80 from the handle C.

What we claim as new, and desire to secure by Letters Patent, is—

1. In a hod, the combination of the sheet-metal body portion A, formed with sides A', 85 having flanged edges, a continuous spring t, re-enforcing the lateral and forward edges of the sides A', and braces B, terminating in a socket for the handle C and provided with curved arms q', extending to the forward 90 ends of the sides about midway between the upper and lower edges of the latter, and maintained against the spring t by the flanged edges of the sides, and arms q², extending toward the rear edges of the sides, substantially 95 as described.

2. In a hod, the combination, with the body portion and handle, of a sheath *o*, extending longitudinally of the lower edge of the body portion toward the rear end thereof, and an 5 adjustable and removable spring-rest *D*, having an arm *p* extending into the sheath at its rear end and a curved free arm *p'* extending below the sheath, with its free end toward the

handle, substantially as and for the purpose set forth.

LOUIS L. SCHUBERT.
FREDERICK MAIERHOFER.

In presence of—
J. W. DYRENFORTH,
M. J. BOWERS.
